SPARK PLUG

Cyril G. Cramer, Binghamton, N. Y.

Application July 1, 1936, Serial No. 88,457

2 Claims. (Cl. 123—169)

My invention relates to spark plugs and more particularly to a plug so constructed as to produce a plurality of sparks, and it consists in the constructions, arrangements and combinations herein described and claimed.

It is an object of my invention to provide a spark plug in which the positive electrode of the plug is formed as a series of spark-gaps, a spark occurring at each of the gaps, thereby assuring perfect ignition of the fuel.

It is a further object of the invention to provide a plug which may be readily assembled and dismantled for cleaning.

It is a still further object of the invention to provide a plug in which the plug shell, the insulator and the plug head are so formed interiorly as to produce an ignition chamber.

Additional objects, advantages and features of invention will be apparent from the following description considered in conjunction with the accompanying drawing, wherein,

Figure 1 is a vertical sectional view of a plug constructed in accordance with my invention.

Figure 2 is a cross section on the line 2—2 of Figure 1.

Figure 3 is a plan view of an insulator employed in the plug.

In carrying out my invention I provide a metallic shell 10 having a threaded nipple 11, at one end, for securement of the plug in an engine head, as is customary. The upper portion of the shell is preferably hexagonal in cross section, for ready manipulation by the use of a wrench.

The nipple 11 includes a bore 12, the surface of which is flared outwardly as at 13, and thence extended in a horizontal plane forming an annular seat 14. From the seat 14 the surface extends longitudinally of the shell 10, as at 15, forming an annular well, being interiorly threaded at its upper termination for reception of a packing gland 16.

Upon the seat 14, I provide a gasket 17, the bore of which stops flush with flared wall 13, and the outer circumference of which is slightly less than the annular well. An annular, insulator 18 is positioned upon the gasket 17, and a similar gasket 19 is disposed upon the upper face of the insulator against which the gland 16 may engage. The bores of the insulator and the last named gasket are the same as the gasket 17 so that a smooth uninterrupted surface is presented, and the gland 16 is undercut as at 20 and aligned with the bore of the gasket 19. It will thus be seen that a chamber, generally indicated at 21, is provided which functions as a firing chamber.

The gland 16 has an axial screw threaded bore 22 opening upon the undercut portion 20 and at a suitable point is provided with a shoulder 23 forming a seat for the enlarged portion 24 of an elongated insulator 25. A screw threaded gland 26 is engaged with the threads of the bore 22 for maintaining the insulator 25 in position, and preferably packing rings 27 are employed in conjunction with the enlargement 24, the shoulder 23 and gland 26, to effect a gas-tight connection.

The insulator 25 includes an electrode 28, the lower end of which terminates approximately medially of the height of the insulator 18, for a purpose as will presently appear, and the upper end of the electrode includes a binding screw and nut 29 whereby connection may be made with a wire of an ignition system.

Referring now to Figures 2 and 3 of the drawing, particularly, the shell 10 has a lug 30, extended inwardly of the annular well 15 adapted to engage within a complementary notch 31 formed in the outer face of the insulator 18. The lug 30 is of slightly less length than the depth of the notch 31, thus stopping short of the inner wall of the notch.

An electrode 32 is embedded in the insulator 18 extending axially therefrom and stops short of the electrode 28 a necessary distance to form a spark gap. The insulator 18 further includes a series of electrodes 33, suitably spaced in annular formation, each of which comprises a right angularly disposed arm 34, extended in the direction of the next adjacent arm, but stopping short of contacting relation therewith. Thus, it will be apparent that a spark gap is formed between each arm 34 and the next adjacent electrode. Any desired number of electrodes 33 may be included but the last electrode designated 33a must be positioned so as to align medially of the notch 31. This latter electrode must project a short distance inwardly of the notch so as to readily contact the lug 30 in order to complete the circuit through the plug.

The operation

The operation will be readily understood from the following description, assuming that an engine is equipped with my plugs. The suction stroke of the pistons of an engine will draw in the explosive mixture; the next action occurring will be the compression of the charge in the compression chamber of the engine, but compression of the gas also occurs in the chamber 21 of the plugs. Thus there is a highly ignitable mixture around the electrodes 28, 33 and 33a. When

ignition occurs, it will be apparent that a spark will occur between each electrode, thereby producing a circular formation of fire which is highly effective upon the explosive mixture in the explosive space of the motor, consuming the mixture thoroughly, thereby causing the power stroke. Then the exhaust stroke occurs, as customary, completing the cycle of the engine.

- 5 It will be apparent that with the use of my plug, 10 the motor as well as the plug itself will be kept free of carbon accumulations, due to the efficient and ample spark producing thorough burning of all combustible fuel as well as residue which may be present. Also by providing a plug 15 with a series of sparks a quicker starting of a motor is made possible as well as effecting economy in fuel consumption and obviously produces increased power.

While I have shown and described a preferred 20 form of the invention, this is by way of illustration only, and I consider as my own all such variations in construction as fairly fall within the scope of the appended claims.

- I claim:
- 25 1. A spark plug having a casing, an insulator ring therein, a gland for securing the ring in position, said casing ring and gland having an interior structure defining a chamber, a positive electrode carried by the gland, said electrode termin-

nating medially of the chamber, a plurality of electrodes mounted in the insulator ring disposed axially therefrom and spaced with respect to one another to define spark-gaps, one of said electrodes extending into close relation with the positive 5 electrode to define a spark-gap, and one of said second named electrodes having contacting relation with the casing.

2. A spark plug comprising a casing having a well medially thereof, an insulator ring seated in the well, a gland cooperable with the casing for securing the ring in position, said casing and gland having portions shaped for cooperation with the walls of the ring to define a chamber, the periphery of said ring having an inwardly 15 directed notch, a lug on the interior of the casing and projecting into the notch, a positive electrode carried by the gland, said electrode terminating medially of the chamber, a plurality of electrodes mounted in the insulator ring disposed axially 20 therefrom, each electrode having a right angular portion stopping closely adjacent the next electrode to define a spark gap, the first of said electrodes extending into close relation with the positive electrode to define a spark gap, and the 25 last of said second named electrodes having contacting relation with the lug of the casing.

CYRIL G. CRAMER.
